(57) **CLAIM**

The ornamental design for a sleeping bag, as shown and described.

DESCRIPTION

FIG. 1 is a front, right, and top perspective view of a sleeping bag, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is another front, right, and top perspective view of the sleeping bag in another state of FIG. 1.

The broken lines shown in the drawings are included for the purpose of illustrating portions of the sleeping bag that form no part of the claimed design.

1 Claim, 8 Drawing Sheets
